UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

STOKER.

Application filed October 16, 1923. Serial No. 668,798.

To all whom it may concern:

Be it known that I, EDWIN LUNDGREN, a citizen of the United States, residing at Frederick, county of Frederick, State of Maryland, have invented a certain new and useful Improvement in Stokers, of which the following is a full, clear, and exact description.

My invention relates to furnaces and has special reference to furnaces of the multiple retort underfeed stoker type.

An object of the invention is to provide a novel and improved stoker of this type.

Another object of the invention is to provide novel and improved fuel supporting and air supplying means for a stoker of this type.

Another object of the invention is to provide an underfeed stoker in which the air from the wind box is evenly distributed to the fuel throughout the area of the underfeed grate section.

The several features of the invention, whereby the above mentioned and other objects of the invention may be attained, will be clearly understood from the following description and accompanying drawings, in which—

Figure 1 is a longitudinal sectional view, partly in elevation, of a portion of an underfeed stoker embodying the features of the invention in their preferred form;

Fig. 2 is a transverse sectional view, on an enlarged scale, taken on the line 2—2 of Fig. 1;

Fig. 3 is a sectional view, on an enlarged scale, taken on the line 3—3 of Fig. 2; and

Fig. 4 is a detail bottom plan view of one of the tuyère blocks employed in the stoker.

The furnace illustrated in the drawings is of the type of the one illustrated and described in the patent to Riley No. 1,322,822, dated Nov. 25, 1919. As shown this furnace comprises an underfeed grate 2, and an overfeed grate 4 at the rear thereof. The underfeed grate comprises a plurality of downwardly and rearwardly inclined retorts 6 arranged side by side and spaced apart with the outer walls of the outer retorts spaced from the side walls of the furnace. Each of the retorts is provided with a bottom wall 8 and side walls 10. The bottom walls 8 of the several retorts form continuations of the bottom

walls, respectively, of the fuel hoppers 12, the fuel from the hoppers being fed into the retorts by means of horizontally reciprocating plungers 16. On the upper edge of each of the side walls of the retorts is mounted a row of tuyère blocks 18, the rows of tuyère blocks mounted on the adjacent walls of the retorts being arranged side by side with their inner surfaces in sliding engagement, and the rows of tuyère blocks mounted on the outer walls of the outer retorts extending over the spaces between the outer walls and the side walls of the furnace. The overfeed grate is made up of a plurality of sections arranged side by side, each of which is associated with one of the side walls of one of the retorts and these parts together with the row of tuyère blocks supported on the side wall are adapted to be moved together as a unit back and forth in a substantially horizontal direction so as to effect the feed of the fuel progressively while in the course of combustion, and the discharge of the refuse of the fuel into the usual ash pit located at the rear of the overfeed grate. To enable said units to be thus moved back and forth, each overfeed grate section is mounted on a shoe 22 adapted to slide horizontally on a support 24, the lower or rear end of the associated retort side wall being pivotally connected at 26 to the shoe and its upper or forward end being suitably mounted for sliding movement. The means for actuating the several movable units, as above described, comprises links 28 connecting the forward ends of the walls of each retort with the feeding plungers 16 associated with the retort.

Except as hereinafter described, the parts above referred to may be and preferably are the same as the corresponding parts of the stoker illustrated and described in said patent to Riley No. 1,322,822 to which reference may be had for more complete description of the same.

In the embodiment of the present invention illustrated in the drawings a tuyère structure comprising a row of tuyère blocks 30 is mounted on the bottom wall of each retort. These tuyère blocks are arranged one upon another in overlapping relation and may be of a common construction, each having a depending hook-shaped lug 32 that extends through an opening 34 in the top

2
wall of the block upon which it rests and hooks under the rear end wall of the opening, the depending hook-shaped lug of the lowermost block extending through an opening 36 in the bottom wall and hooking over the rear end wall of this opening, so as to detachably secure the tuyère blocks together and to hold them in position on the bottom wall. Each tuyère block is provided with the usual top wall 38 and side wall 40 having its lower edge corrugated so as to form tuyère openings 42, the bottom wall of the retort being provided with a longitudinally extending opening 44 for supplying air to the tuyère openings 42 of the blocks from the wind box of the furnace. The top surface of the uppermost tuyère block 30 is arranged substantially in the plane of the bottom wall of the fuel hopper 12.

10 With this construction it will be apparent that during the operation of the stoker fuel will be fed by the plungers 16 from the hoppers 12 into the upper ends of the fuel retorts, over the top surface of the uppermost tuyère block 30 of each row, and down over these rows of tuyère blocks. Also this feeding operation causes the fuel to be forced up over the tuyère blocks 18 on the side walls of the retorts, the reciprocation of the side walls of the retorts and the tuyère blocks 18 carried thereby acting to uniformly feed the fuel downwardly over these tuyère blocks and also downwardly over the tuyère blocks 30. It will be apparent that the rows of tuyère blocks 30 not only constitute the bottoms of the retorts over which the fuel is fed to the tuyère blocks 18, but also as they extend substantially the entire width of the retorts, and the top surface of the uppermost block 30 of each row is substantially in the plane of the bottom wall of its associated hopper 12, they constitute active overfeed grate sections that cooperate with the tuyère structures 18 to evenly distribute air from the wind box to the fuel throughout the entire width of the furnace. Thus a uniformly active fuel burning surface is provided that extends the entire width of the fire box of the furnace, and is made up of a plurality of underfeed and overfeed grate sections alternately arranged side by side.

15 As will be evident to those skilled in the art, my invention permits of various modifications without departing from the spirit thereof or the scope of the appended claims.

What I claim is:

1. A furnace having, in combination, a downwardly and rearwardly inclined fuel retort having side walls longitudinally movable and a downwardly and rearwardly inclined bottom wall, tuyère structures mounted on said side walls, means for reciprocating said side walls longitudinally and for feeding fuel into the forward end

of the retort, and a row of tuyère blocks one upon the other in overlapping relation mounted on the inclined bottom wall of the retort spaced a distance below the top surfaces of said first mentioned tuyère structures and extending substantially the width of the retort.

2. A furnace having, in combination, a downwardly and rearwardly inclined fuel retort having side walls longitudinally movable, tuyère structures mounted on said side walls, means for reciprocating said side walls longitudinally and for feeding the fuel into the forward end of the retort, and a tuyère structure mounted on the inclined bottom wall of the retort of substantially the width of and extending substantially the length of the retort for supplying air to the fuel throughout substantially the area of the retort.

3. A furnace having, in combination, a downwardly and rearwardly inclined fuel retort having side walls longitudinally movable, tuyère structures mounted on said side walls, means for feeding the fuel into the forward end of the retort comprising a hopper having its bottom wall forming substantially a continuation of the bottom wall of the retort, means for reciprocating said side walls longitudinally and for feeding fuel into the forward end of the retort, and a row of tuyère blocks mounted on the bottom wall of the retort arranged one above the other in overlapping relation, spaced a distance below the top surface of said first mentioned tuyère structures and extending substantially the width of the retort, the top surface of the uppermost tuyère block in the row being arranged substantially in the plane of the bottom wall of said hopper.

4. A furnace having, in combination, a downwardly and rearwardly inclined fuel retort having side walls longitudinally movable and a bottom wall inclined downwardly and rearwardly, tuyère structures mounted on said side walls, means for feeding the fuel into the forward end of the retort comprising a hopper having its bottom wall forming substantially a continuation of the bottom wall of the retort, and a row of tuyère blocks mounted on the bottom wall of the retort arranged one above the other in overlapping relation, spaced a distance below the top surface of said first-mentioned tuyère structures and extending substantially from the lower end of the retort to a point so as to position the top surface of the uppermost tuyère block substantially on the level with said bottom wall of said hopper, said bottom wall of the retort having an air supplying opening, and the interior of said last-mentioned row of tuyère blocks being in communication therewith.

EDWIN LUNDGREN.
